(57) CLAIM

The ornamental design for a golf grip, as shown and described.

DESCRIPTION

FIG. 1 is a perspective view of the golf grip;

FIG. 2 is a top plan view thereof;

FIG. 3 is a bottom plan view thereof;

FIG. 4 is a right side view thereof;

FIG. 5 is a left side view thereof;

FIG. 6 is a front view thereof;

FIG. 7 is a rear view thereof; and,

FIG. 8 is an enlarged break out view taken in circle 8 of FIG. 2.

The dash-dot dash broken line disclosed on FIG. 2 forms no part of the claimed design.

The broken lines in the drawings depict environmental subject matter of the golf grip only and form no part of the claimed design.
